TRASH RECEPTACLE

Felice Pipolo, 270 Bellingham Drive,
Williamsville, N.Y. 14221

Filed May 8, 1969, Ser. No. 17,086

Term of patent 14 years

Int. Cl. D7—99

U.S. Cl. D49—35

FIG. 1 is a front perspective view of a trash receptacle showing my new design;

FIG. 2 is a rear elevational view thereof;

FIG. 3 is a top plan view thereof; and

FIG. 4 is a bottom plan view thereof.

The characteristic features of my design reside in the specific configuration of the receptacle hood as best illustrated in FIGS. 1 and 3 on the drawing.

I claim:

The ornamental design for a trash receptacle, as shown and described.
